UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed October 26, 1923. Serial No. 670,825.

This invention relates to stencil card-holders, and associated ribbon-feeding mechanism for typewriting machines; that is to say, to means whereby stencil cards 5 may be held to the platen and line-spaced over the same, while a ribbon for staining, and thereby rendering visible, the stencil cuts, is fed over the platen between the latter and the stencil card.

10 Ribbons for this purpose are ordinarily ribbons of the breadth of the stencil, fed around the platen, instead of lengthwise thereof, so as not to be affected by the movement of the stencil with the platen in letter-feed and return directions. Heretofore 15 such ribbons have been automatically fed in one direction and hand-wound in the other direction; or, when automatically fed in one or both directions, have been fed 20 through connections from the platen, and by line-space feed of the platen. In the use of the machine for the stenciling of cards, however, the card-holders may be line-spaced without line-spacing of the platen; 25 and this is desirable since it relieves the line-spacing mechanism of the work of turning the platen. Nevertheless, the ordinary platen-line-spacing mechanism may be employed to line-space the card-holder, 30 through the expedient of having connections, from such line-spacing mechanism, to both the card-holder and the platen, and disconnecting such line-space mechanism from the platen when the card-holder is to be 35 used.

An object of the present invention is the provision of means, in mechanism of the general character mentioned, whereby the ribbon may be fed automatically in either 40 direction, at will, and without movement of the platen or type-keys.

A feature of the invention, in the preferred embodiment thereof, is a ribbon-feeding mechanism operable by the card-holder 45 in the movements of the latter, incidental to line-spacing thereof and return of the same to initial position, in stenciling the successive cards.

A further feature of the invention may

be the use of the platen-line-spacing means 50 in effecting feed of the ribbon; preferably by connections from such platen-line-spacing means, through the card-holder, to the ribbon-feeding mechanism.

In its preferred form, a feature of the 55 invention may reside in a mounting of the ribbon-holding devices, spools for instance, and of the ribbon-feeding mechanism, on a card-holder frame, so that the same, together with the card-holder, and without 60 any assembling or disassembling, may, as a unit, be placed upon, detachably secured to, and removed from, the platen-frame.

Other features and advantages will hereinafter appear. 65

In the accompanying drawings, 70 Figure 1 is a view, in front elevation, of a platen-frame and associated parts of a typewriting machine embodying the present invention.

Figure 2 is a top plan view of the apparatus shown in Figure 1.

Figure 3 is a view, in side elevation, taken on the line 3—3 of Figure 1, showing the platen and card-holder line-spacing mechanisms and ribbon-feeding mechanism; the card-holder being in its lowermost or normal position, and the ribbon-feeding mechanism being shown as functioning on the left-hand ribbon-spool. 75

Figure 4 is a view, in side elevation, on the line 4—4 of Figure 1, showing the ribbon-feeding mechanism functioning on the right-hand ribbon-spool. 80

Figure 5 is a view similar to Figure 3, 85 except that the card-holder line-spacing mechanism is more fully shown, and the card-holder is line-spaced upward from its Figure 3 position.

Figure 6 is a view, in side elevation, on the line 6—6 of Figure 2, showing a cross-section of the card-holder and showing the ribbon. 90

The platen 10, which may be of metal, is fixed to an axle 11 journaled in the side plates 12 of the platen-frame. The platen may be rotated by means of the usual finger-wheels 13, or by means of a line-space 95

ratchet-wheel 14. The latter may turn freely without movement of the platen, or may be locked to the platen-axle to cause the platen to have line-feed rotation when the line-space mechanism is operated. A finger-piece 15, movable in and out longitudinally of the left-hand end of the platen-axle, operates a clutch-device, not shown, for locking the ratchet-wheel to the platen and for releasing the platen from the line-space mechanism. This clutch-device may be that shown in United States Letters Patent to Helmond, No. 1,150,366, dated August 17, 1915, and so is not described in detail here. The line-space mechanism for rotating the ratchet-wheel 14, which may be that found in the Underwood standard typewriting machine, comprises a slide or plunger 17 movable forward and backward on the left-hand frame-piece 12 and carrying a pawl 18 for engagement with the teeth of the ratchet-wheel. A spring 19, secured at 20 to the slide 17 and secured at 21 to the side piece 12, acts to hold the slide forward in its normal position and to return it to such position when free to do so. A line-space lever, in the form of a bell-crank 22 pivoted at 23 to the side piece 12, has one arm 24 thereof disposed for engagement with an offset 25 on the forward end of the slide 17; so that, when the lever 22 is thrown to the right, the slide is moved back against the action of the spring 19 to effect line-feed of the ratchet-wheel.

As hereinbefore mentioned, the card-holding device, including all parts thereof and actuating mechanism therefor, may be affixed as a unit to the platen-frame and removed as a unit therefrom, according to the intended use of the machine. It therefore has its own frame-members, which consist of flat end plates 39 which are tied together by a rod 40, adapted to be set upon the usual flat upper offsets or flanges 41 of the side pieces 12 of the platen-frame.

Journalized in depending ears 52 on the side plates 39 of the card-holder frame is a rock-shaft 53. Fast on the rock-shaft 53 are a pair of arms 54 (see Figures 2, 3 and 6), which extend up from the rock-shaft 53 and thence forwardly well above the platen. The forward ends of the arms 54 are turned downward, as at 55. A frame 56, on which the stencil-cards are directly supported, has upturned ears 57 at the ends thereof, by means of which it is pivotally mounted at 58 on the ends 55 of the arms 54. Coil-springs 59, secured at one end to lugs 60 on ears 57, and at the other end to pins 61 on the arms 54, serve to hold the frame 56 in such position that the stencil will properly lie against the platen. Stop-pins 62 on the lugs 60, by engagement with shoulders 63 on the arms 54, determine the desired setting of the stencil-frame with respect to the platen.

The stencil-frame comprises an upper cross-reach 64, having a central upper bend 65 therein to permit of insertion of the operator's fingers for placement or removal of a stencil-card. On the cross-reach 64, at each side thereof, is a forwardly-extending ear 66 of the general curvature of the platen; and secured to the ears 66 are the laterally-projecting ears 67 of a plate comprising side pieces 68 which extend forward and downward to follow the general curvature of the platen so as to be set snugly thereto. At their lower ends the side pieces 68 have soldered to the front face thereof a thin metal strip 69, which forms a cross-reach 70 and ties together the side pieces 68 into a single plate. The side pieces 68, together with the upper cross-reach 64 and the lower cross-reach 69, therefore, form a frame with an opening therein which is rectangular except for the bend 65, for the operator's fingers, at the upper portion thereof. The plate forming the lower cross-reach 69 of this frame is turned rearwardly around the lower edges of the side pieces 68, and is thence turned upward at 70 to form a pocket or seat for the stencil-cards; the upturned lip of this pocket-piece 69—70 being spaced sufficiently from the rear faces of the frame-members 68 to permit of easy insertion of 80 the stencil-cards therebetween.

A stencil-card 80 is shown in position in the card-holder. This stencil-card comprises a rectangular cardboard frame 81, to the rear of which is pasted the stenciling sheet 82. When the card is in position, with its lower edge seated in the pocket 69—70 and with its side margins in proper position, the stenciling sheet 82 is seen through the card-holder frame 56, 68—69, and is in position 100 to receive type-impressions. In inserting the stencil-card, it is passed down in front of the upper cross-reach 64 of the card-holder frame, and thence down behind the side reaches 68.

It has been stated that the arms 54 of the card-holder are on the rock-shaft 53. This is to permit the card-holder to be line-spaced upward around the axis of the shaft 53. The curvature of the card-holder is such 115 as to hold the card properly to the platen, between the latter and the usual type-bar guide, in any angular position of the arms 54. In Figure 6, the card-holder is shown as having been swung down so that the type 120 95 may write on the upper portion of the latter. The card is shown as of such length that at least five lines may be written thereon; as the card-holder is progressively stepped or line-spaced upward.

To effect such line-space movement of the card-holder from the platen line-space mechanism heretofore described, the following mechanism is employed. Fast on the shaft 53 is a segmental ratchet-plate 96. Loosely 130

pivoted on the shaft 53 is an arm 97 having pivoted thereto, at its forward end, a pawl 98 for engagement with the teeth 99 on the plate 96. A coil-spring 100, connected to the arm 97 and to the pawl 98, when free to do so, throws the pawl into engagement with the teeth, and holds the same in operative engagement with the teeth. When the arm 97 is forced to its lowermost position, however, a dog 101 on the pawl, by engagement with a pin 102 on a bracket 103 depending from the side piece 39 of the card-holder frame, causes the pawl to be rocked and held out of engagement with the teeth 99. A leaf-spring 104, bearing on the upper edge of the arm 97 and secured to a pin 105 on the card-holder-frame side piece 39, presses down the arm 97 to release the pawl 98 from the teeth 99 and to hold the pawl normally out of engagement with the teeth 99 against the action of the spring 100; the leaf-spring 104 being sufficiently stronger than the spring 100 to effect this result.

The arm 97, at its forward end, is turned up at 106, and is thence turned leftward at 107, and downward at 108, to form a U (see Figures 1 and 5). The downturned portion 108 of this U member (see Figure 3) normally lies in the path of rearward movement of the offset 25 on the forward end of the platen line-space slide 17. This downturned U portion 108 has also an inclined or cam edge 109, against which the slide 17 acts when the same is thrust rearward. It follows that, upon rearward thrust of the slide 17, on operation of the line-space lever 22, the arm 97 is rocked upward against the action of the leaf-spring 104. The first effect of this upward movement is to release the pawl so that it may engage the teeth 99 on the segment-plate 96. Thereupon, the forcible upward movement of the arm 97, by means of the slide 17, causes the segment-plate 96 to move up, and, by means of the shaft 53 to which it is fast, to correspondingly move up the card-holder. This upward movement will be a one-step line-space movement. Upon release of the line-space lever, the spring 104 throws the arm 97 back to its normal position; that is to say, into position for engagement of the pawl 98 with the next succeeding tooth 99 upon the next operation of the line-space lever.

A spring-detent 110, by engagement with the teeth 99, may serve to hold the segment-plate 96 and card-holder, against accidental displacement, in the position to which they have been line-spaced. After stenciling on a card has been completed, and when the stencil-card has been removed and replaced by another card, the card-holder, together with the segment-plate 96, may be thrust down by means of a finger-piece 111 on the segment-plate 96, or by means of finger-pieces 112 on the card-holder-supporting arms 54. The lowermost position of the card-holder may be determined by engagement of the pin 105 on the card-holder-frame side piece 39 with the upper end of a slot 113 in the segmental ratchet-plate 96. Engagement of pin 105 with the lower end of the slot 113 may determine the uppermost position to which the card-holder may be moved.

As line-space movement of the platen is unnecessary in the use of the present invention, the ratchet-wheel 14, as hereinbefore suggested, may be unlocked from the platen so that operation of the line-space lever 22, to line-feed the card-holder, will have no effect upon the platen. This makes easier the effort of line-spacing the card-holder, and permits the rear pressure-rolls to be left in their normal position against the platen.

A ribbon 115 (see Figure 6) is shown as having one end attached to, and wound upon, a spool 116, whence it passes around the platen, and at its other end is attached to, and wound upon, a spool 117. The spools 116 and 117 are journaled in plates or brackets 118, set upon and movable as a unit with the card-holder frame. The shaft 40 of the card-holder frame passes through the brackets 118; and the latter are held against lateral outward displacement on the shaft 40 by means of collars 119, and against displacement towards each other by means of spool-hubs 120. The shaft 53 prevents rocking of the brackets 118 on the shaft 40; and, to this end, the brackets 118 are slotted at 121 to receive, and rest upon, the shaft 53.

Fixedly connected to the spools 116 and 117 are ratchet-wheels 122 and 123, respectively. Co-operating with the ratchet wheels 122 and 123, to effect ribbon-feed rotary movement of the same, are pawls 124 and 125, respectively; these pawls being pivotally mounted at 126 and 127 on a rockable hand-lever 128, having a handle 128^a on the upper end thereof. The hand-lever 128, as indicated in Figures 3 and 4, is for the purpose of determining upon which of the spools 116 and 117 the ribbon-feeding mechanism shall function; or, in other words, for determining the direction of feed of the ribbon. In Figure 3, the lever 128 is shown as pulled forward to cause the pawl 125 to co-operate with the ratchet-wheel 123, the pawl 124 being then disabled; and, in Figure 4, the hand-lever 128 is shown as thrown rearward to disable the pawl 125, and to position the pawl 124 for action on the ratchet 122. Each of the pawls 124 and 125 is provided with a tail 129; the tails 129 being connected by a spring 130 which tends to draw the same together, and thereby rock the pawls toward the ratchet-wheels. The head 131 of a stud 132 serves as a stop for both pawls (see Figures 110, 115, 120, 125, 130).

3 and 4); so that the spring 130 cannot throw the pawl, which is intended to be disabled, into engagement with its ratchet-wheel, and so that the spring may have a set anchorage to enable it to properly function upon the pawl which is intended to be effective on its ratchet-wheel.

The lever 128, which supports the pawls, is itself supported and pivotally connected by means of the stud 132 to one arm 134 of a bell-crank lever pivoted at 135 to the right-hand face of the left-hand bracket-plate 118. The hand-lever 128, on the other hand, is on the left-hand side of the left-hand bracket-plate 118, and, consequently, the stud 132 extends through an opening 136 in this bracket-plate. The other arm 137 of the aforesaid bell-crank lever is connected by means of a link 138 with the right-hand card-holder arm 54; the connections 139 and 140 of the link 138 to the arms 137 and 54, respectively, being pins on which the link 138 may freely rock.

It follows from the connections aforesaid that, as the segmental ratchet 96 is fed upward with the card-holder, the link 138 is forced upward from Figure 3 to Figure 5 position, and the bell-crank 134—137 is rocked counterclockwise to cause the pawl 125 (Figures 3 and 5) and 124 (Figure 4) to ride idly over the teeth of the corresponding ratchet, according to which of the Figures 3 and 4 settings is had. When, however, after stenciling on a card has been completed, the card-holder is thrown down from Figure 5 to Figure 3 position, the link 138 is pulled downward, and the bell-crank 134—137 rocked clockwise to cause the effective one of the pawls 124 or 125 to rotate the corresponding ratchet-wheel and ribbon-spool. In other words, the ribbon gets one feed in one or the other direction every time the card-holder is thrown to normal position for commencement of writing on a new stencil.

Dogs or detents 141 may serve to hold the spools against accidental unwinding; and the pin 135, which serves as a pivot for the bell-crank 134—137, may also serve as a support on which these dogs or detents are pivotally mounted. A spring 142, which connects the tail-pieces 143 of the detents 141, urges the latter toward the ratchets 123 and 122. Stop-pin 145, when engaged by the detents 141, holds the latter out of engagement with the ratchet-wheels. In Figure 3, the stop 145 is shown as holding one detent 141 from the ratchet 122, so that the spool 116 may rotate to permit the ribbon to be drawn therefrom while the spool 117 is being fed to pick up the ribbon; the other detent 141 at this time being in engagement with the ratchet 123 to hold the latter after feed thereof. In Figure 4, on the other hand, the stop-pin 145 is holding one detent

141 from engagement with the ratchet 123, while the other detent 141 engages with the ratchet 122, for feed of the ribbon in the opposite direction. The stop 145 when engaged by one of the detents also acts as an anchorage for the spring to cause the latter to act effectively in holding the other detent in operative position.

Since the pawl-carrying and setting lever 128 is itself bodily swung between Figure 3 and Figure 4 positions with the bell-crank 134—137, and, since the pivot-pin 132 of this lever 128 passes through the bracket-plate 118, the hole 136, through which the pin 132 passes, is elongated as shown in Figure 3. The pawl-setting lever 128 carries a pin 146, by means of which it may be held in either its Figure 3 or Figure 4 position. For this purpose, the pin 146, in Figure 3 position of the lever 128, engages a shoulder 147, and, in Figure 4 position of the lever 128, a shoulder 148 on a stop-arm 149. This arm 149 is conveniently loosely pivoted on the pin 139 which connects the bell-crank arm 137 and the link 138 at the upper end of the latter. The other end of the arm 149 has an ear 151 offset therefrom, to which is connected one end of a spring 152, the other end of the spring 152 being connected to a pin 153 on the bracket 118. The spring 152 exerts a downward pull on the stop-arm 149. Between the shoulders 147 and 148 on the arm 149, the latter is bellied outward, as shown at 154, to form a cam-surface, by means of which the pin 146 is held to whichever the stops 147 and 148 it may be brought; and by means of which the stop-arm 149 may be cammed upward against the resistance of the spring 152 to permit movement of the hand-lever 128 between Figures 3 and 4 positions.

Variations may be resorted to within the scope of the invention, and portions of the improvements may be used without others.

Having thus described my invention, I claim:

1. In a typewriting machine, a platen, a card-holder mounted for line-space movement, ribbon-feeding means arranged to feed the ribbon around the platen, and means for actuating the ribbon-feeding means directly from movement of the card-holder.

2. In a typewriting machine, a platen, a card-holder mounted for line-space movement, ribbon-feeding means arranged to feed the ribbon around the platen, and means for actuating the ribbon-feeding means in either direction directly from movement of the card-holder.

3. In a typewriting machine, a platen, a card-holder mounted for line-space movement, ribbon-feeding means arranged to feed the ribbon around the platen, means for actuating the ribbon-feeding means di-

rectly from movement of the card-holder, and means for setting the ribbon-feeding means for feed of the ribbon in either direction.

5. In a typewriting machine, a platen, a card-holder mounted for line-space movement over the platen without movement of the platen, ribbon-feeding means arranged to feed the ribbon around the platen, and means for actuating the ribbon-feeding means directly from movement of the card-holder.

10. In a typewriting machine, a platen, a card-holder, means for effecting line-space movement of the card-holder over the platen while the platen is motionless, ribbon-feeding means, and means for actuating the ribbon-feeding means from the card-holder upon movement of the latter to its initial

20. position.

6. In a typewriting machine, a platen, a card-holder, means for effecting line-space movement of the card-holder over the platen, ribbon-feeding means, and means for actuating the ribbon-feeding means from the card-holder upon movement of the latter to its initial position.

7. In a typewriting machine, a revolute platen, a pivoted card-holder, means for effecting line-space movement of the card-holder, around its pivot, over the platen, ribbon-feeding means, and means for actuating the ribbon-feeding means from the card-holder upon movement of the latter to its initial position.

8. In a typewriting machine, a platen, a card-holder, means for effecting line-space movement of the card-holder over the platen while the platen is motionless, means for returning the card-holder to initial position over the platen, ribbon-feeding means, and means for actuating the ribbon-feeding means from the card-holder upon movement of the latter to its initial position.

45. 9. In a typewriting machine, a platen, a card-holder, means for effecting line-space movement of the card-holder over the platen, means for returning the card-holder to initial position over the platen, ribbon-feeding means, and means for actuating the ribbon-feeding means from the card-holder upon movement of the latter to its initial position.

55. 10. In a typewriting machine, a revolute platen, a pivoted card-holder, means for effecting line-space movement of the card-holder, around its pivot, over the platen, means for returning the card-holder to initial position over the platen, ribbon-feeding means, and means for actuating the ribbon-feeding means from the card-holder upon movement of the latter to its initial position.

60. 11. In a typewriting machine, a revolute platen, a pivoted card-holder mounted for

line-space movement, around its pivot, over the platen, ribbon-feeding means arranged to feed the ribbon around the platen, and means connected to the card-holder for actuating the ribbon-feeding means upon movement of the card-holder.

12. In a typewriting machine, a platen, line-space mechanism for the platen, means for disconnecting the platen from its line-space mechanism, ribbon-feeding mechanism arranged to feed the ribbon around the platen, and means for actuating the ribbon-feeding mechanism from the platen line-spacing mechanism when the platen is disconnected from the latter.

15. In a typewriting machine, a platen, line-space mechanism for the platen, means for disconnecting the platen from its line-space mechanism, a card-holder mounted for line-space movement, means for effecting line-space movement of the card-holder from the platen line-space mechanism when the latter is disconnected from the platen, ribbon-feeding mechanism arranged to feed the ribbon around the platen, and means for actuating the ribbon-feeding mechanism from movement of the card-holder.

20. 14. In a typewriting machine, a platen, line-space mechanism for the platen, means for disconnecting the platen from its line-space mechanism, a card-holder mounted for line-space movement, means for effecting line-space movement of the card-holder from the platen line-space mechanism when the latter is disconnected from the platen, ribbon-feeding mechanism arranged to feed the ribbon around the platen, and means for actuating the ribbon-feeding mechanism from movement of the card-holder to initial

25. position.

15. In a typewriting machine, a platen, line-space mechanism for the platen, means for disconnecting the platen from its line-space mechanism, a card-holder mounted for line-space movement, means for effecting line-space movement of the card-holder from the platen line-space mechanism when the latter is disconnected from the platen, ribbon-feeding mechanism arranged to feed the ribbon around the platen, means for setting the ribbon-feeding mechanism for a predetermined throw of the latter, and means for actuating the ribbon-feeding mechanism after the setting thereof from movement of the card-holder.

30. 16. In a typewriting machine, a platen, line-space mechanism for the platen, means for disconnecting the platen from its line-space mechanism, a card-holder mounted for line-space movement, means for effecting line-space movement of the card-holder from the platen line-space mechanism when the latter is disconnected from the platen, ribbon-feeding mechanism arranged to feed the ribbon around the platen, and means for

setting the ribbon-feeding mechanism, on line-space movement of the card-holder, for a predetermined throw of the ribbon-feeding mechanism, and for actuating the ribbon-feeding mechanism upon return movement of the card-holder to initial position.

17. In a typewriting machine, a revoluble platen, a frame for the platen, a pair of ribbon-spools on the platen-frame, above the platen, from one to the other of which the ribbon may be fed around the platen, a card-holder movable in line-space and return directions over the platen, and means, comprising a pawl-carrier having a pair of pawls, one for effecting a rotary feed of each spool, and an arm connecting the pawl-carrier to the card-holder, whereby to effect rotary feed of the selected spool when the card-holder is moved.

18. In a typewriting machine, a revoluble platen, a frame for the platen, a pair of ribbon-spools on the platen-frame, above the platen, from one to the other of which the ribbon may be fed around the platen, a card-holder movable in line-space and return directions over the platen, and means, comprising a pawl-carrier having a pair of pawls, one for effecting a rotary feed of each spool, a rocker on which the pawl-carrier is mounted, and a link connecting the rocker to the card-holder, whereby to effect rotary feed of the selected spool when the card-holder is moved.

19. In a typewriting machine, a revoluble platen, a frame for the platen, a pair of ribbon-spools on the platen-frame, above the platen, from one to the other of which the ribbon may be fed around the platen, a card-holder movable in line-space and return directions over the platen, and means, comprising a pawl-carrier having a pair of pawls, one for effecting a rotary feed of each spool, a bell-crank lever on which the pawl-carrier is mounted between the spools, and a link connecting the bell-crank lever to the card-holder, whereby to effect rotary feed of the selected spool when the card-holder is moved.

20. In a typewriting machine, a revoluble platen, a frame for the platen, a pair of ribbon-spools on the platen-frame, above the platen, from one to the other of which the ribbon may be fed around the platen, a card-holder movable in line-space and return directions over the platen, means, comprising a pawl-carrier having a pair of pawls, one for effecting a rotary feed of each spool, a rocker on which the pawl-carrier is mounted, and a link connecting the rocker to the card-holder, whereby to effect rotary feed of the selected spool when the card-holder is moved, and means for swinging the pawl-carrier on the rocker to disable one pawl and render effective the other pawl, according to the desired direction of feed of the ribbon.

21. In a typewriting machine, a revoluble platen, a frame for the platen, a pair of ribbon-spools on the platen-frame, above the platen, from one to the other of which the ribbon may be fed around the platen, a card-holder movable in line-space and return directions over the platen, means, comprising a pawl-carrier having a pair of pawls, one for effecting a rotary feed of each spool, a rocker on which the pawl-carrier is mounted, 70 and a link connecting the rocker to the card-holder, whereby to effect rotary feed of the selected spool when the card-holder is moved, means for swinging the pawl-carrier on the rocker to disable one pawl and render 75 effective the other pawl, according to the desired direction of feed of the ribbon, and means for automatically locking the pawl-carrier in each setting thereof.

22. In a typewriting machine, a revoluble platen, a frame for the platen, a pair of ribbon-spools on the platen-frame, above the platen, from one to the other of which the ribbon may be fed around the platen, a card-holder movable in line-space and return directions over the platen, means, comprising a pawl-carrier having a pair of pawls, one for effecting a rotary feed of each spool, a rocker on which the pawl-carrier is mounted, and a link connecting the rocker to the card-holder, whereby to effect rotary feed of the selected spool when the card-holder is moved, means for swinging the pawl-carrier on the rocker to disable one pawl and render effective the other pawl, according 80 to the desired direction of feed of the ribbon, and means for automatically locking the pawl-carrier in each setting thereof, such locking means comprising a pin on the pawl-carrier, a bar having shoulders in two positions thereon, and a spring for pressing the bar against the pin to hold the pin and pawl-carrier against whichever shoulder on the bar the pin may abut.

23. In a typewriting machine, a revoluble platen, a frame for the platen, a pair of ribbon-spools on the platen-frame, above the platen, from one to the other of which the ribbon may be fed around the platen, a card-holder movable in line-space and return directions over the platen, means, comprising a pawl-carrier having a pair of pawls, one for effecting a rotary feed of each spool, a rocker on which the pawl-carrier is mounted, and a link connecting the rocker to the card-holder, whereby to effect rotary feed of the selected spool when the card-holder is moved, means for swinging the pawl-carrier on the rocker to disable one pawl and render effective the other pawl, 110 according to the desired direction of feed of the ribbon, and means for automatically locking the pawl-carrier in each setting thereof, such locking means comprising a pin on the pawl-carrier, a bar having shoulder- 115

ders in two positions thereon, a spring for yieldingly holding the bar against the pin, and a cam-surface connecting the shoulders on the bar, whereby to hold the pin, and consequently the pawl-carrier, in the position to which it may have been set.

24. In a typewriting machine, a platen, a

platen-frame, a card-holder, a frame for the card-holder, detachably secured to the platen-frame, and ribbon-spools on the card-holder frame, from one to the other of which spools the ribbon may be fed around the platen. 10

ALFRED G. F. KUROWSKI.
